UNITED STATES PATENT OFFICE.

ANDREW BAXTER WELSH, OF SUMRALL, MISSISSIPPI.

LUMBER-GAGE.

1,034,547.

Specification of Letters Patent. Patented Aug. 6, 1912.

Application filed July 13, 1911. Serial No. 638,325.

To all whom it may concern:

Be it known that I, ANDREW B. WELSH, residing in the city of Sumrall, county of Lamar, and State of Mississippi, have invented certain new and useful Improvements in Lumber-Gages, of which the following is a specification.

My invention is an improved gage for measuring thickness and width of lumber, and is particularly adapted for use in planning mills and the like, and for carpenters' use in framing.

The invention resides in the provision of a gage strip, along one longitudinal edge of which the strip is recessed with a series of recesses, which progress in length from one end of the strip to the other and are spaced apart, each recess being designed and graduated to represent a stock thickness of lumber. The other longitudinal edge of the blades or strip is cut away to form a series of step portions designed and graduated to indicate widths of stock lumber, the thickness measuring edge of the tool being also adapted for use as a straight edge in laying off lines on a board.

In its more detail nature the invention also resides in those novel details of construction, combination and arrangement of parts, all of which will be first fully described and then be specifically pointed out in the appended claims, reference being had to the accompanying drawings, in which:—

Figure 1 is a perspective view illustrating the gage as applied for use in measuring the thickness of a board. Fig. 2 is a perspective view of the gage illustrating its manner of use in determining the width of a board. Fig. 3 is a perspective view illustrating the use of the tool as a straight edge. Fig. 4 is a side elevation of the tool, the form of the blank being indicated in dotted lines.

Referring to the drawing in which like numerals and letters of reference indicate like parts in all of the figures, 1 designates the blade which, in the process of manufacture, consists of a rectangular strip (see dotted lines in Fig. 4) to which is secured a handle 2, and which is apertured to permit passage of a strap 3, that is adapted to engage the hand of the user, whereby the tool may be flexibly suspended from the hand to permit the user writing down his notes in a note-book. The blade-stock 1, along one longitudinal edge 4, is provided with a se-

ries of recesses 5, extending from one end of the blade to the other and each of a predetermined length to indicate stock thicknesses. Each recess 5 is separated from the other by a short uncut portion of the blade 4*. In the preferred adaptation of the tool, the smaller recess 5 is at the outer end 8, while the larger recess 5 is nearest the stock.

Opposite the edge 4, the other longitudinal edge 6 is cut away to form a series of steps 7, designed to coöperate with the uncut end 8 and serve as a width gage, to determine the width of stock. The steps 7 being graduated according to the stock 70 widths, such as three inches, four inches, 5 inches, etc. up to twelve or more inches. The uncut end 8 is rounded and pointed as at 9 to form a convenient point whereby the operator may use the tool in moving the 75 boards around.

It will be observed that the depths of the cut away portions 5 are uniform so that the inner edges thereof all lie in the same longitudinal line, thus enabling the tool to be 80 used as a straight edge member (see Fig. 3) when it is desired to score lines on a board.

I am aware that prior to my invention, it has been proposed to provide lumber gages in which longitudinal blades are provided, 85 and in which, step cut away portions are produced along both sides or both longitudinal edges of the blade. The tools of this character are only adapted as thickness gages, for the reason that were they made 90 of a length sufficient to serve as width gages as well as thickness gages, the width of the tool blade would be prohibitive to practical use. By my construction I am able to obtain a minimum width of blade since the 95 stepped portions are on one side only. Furthermore, by constructing the tool as shown and described, the operator grasping the tool in the right hand, as indicated in Fig. 1, can determine instantly the thickness of 100 his material, and then by giving the tool a downward movement, in the direction of the arrow in Fig. 1, and at the same time turning the blade through a half turn, it immediately comes into position (see Fig. 105 2) to measure the width of the stock. Thus increasing the rapidity of use as well as the convenience of the tool.

From the foregoing description, taken in connection with the accompanying drawings 110 it is believed and thought the complete construction, operation and advantages of the

invention will be readily apparent to those skilled in the art.

What I claim is:

1. A measuring gage comprising a stock 5 consisting of an elongated rectangular body of uniform thickness throughout, having one longitudinal edge uniformly recessed with a series of recesses of progressively increasing length from one end of the stock 10 toward the other to serve as a thickness gage, said stock having along its other edge a stepped series of cut away portions to serve as a width gage, said stock at its outer end terminating in a hook portion to 15 coöperate with said series of cut away portions, and a handle secured to the inner edge of said stock extending in the same longitudinal direction as said stock, whereby said stock may be turned to bring either gage 20 edge into operative position, said stock having a set of graduations on each side face adjacent to said recesses, said stock having a second set of graduations on each face adjacent to said stepped series of cut away portions, each set of graduations reading from 25 the respective edge adjacent to which they are located, whereby one set of graduations on one face will be "upside down" with relation to the other set of graduations on 30 the same face, all being arranged substantially as shown and for the purposes described.

2. A measuring gage comprising a stock 5 consisting of an elongated rectangular

body of uniform thickness throughout, having one longitudinal edge uniformly recessed with a series of recesses of progressively increasing length from one end of the stock toward the other to serve as a thickness gage, said stock having along its other edge a stepped series of cut away portions to serve as a width gage, said stock at its outer end terminating in a hook portion to coöperate with said series of cut away portions, and a handle secured to the inner end 40 of said stock, and extending in the same longitudinal direction as that of said stock, said stock having an aperture adjacent to said handle, and a strap passing through said aperture for encircling the hand of 45 the user, said stock, said handle, and said strap, being so arranged that the gage may be turned on its longitudinal axis while in the hand of the user without dropping the gage to bring either gaging edge into operative position as required, said stock having two sets of graduations on each side face, one for each gaging edge, the respective sets of graduations reading from the 50 respective gaging edges, the two sets of graduations on a face of the stock being "upside down" with relation to one another, substantially as shown and for the purposes described.
